LOW NOISE ELECTRON GUN

Malcolm R. Currie, Beverly Hills, Calif., assignor to Hughes Aircraft Company, Culver City, Calif., a corporation of Delaware

Application January 8, 1958, Serial No. 707,719

9 Claims. (Cl. 315—3.5)

This invention relates to electron beam tubes, and more particularly to a new low noise electron gun for such devices.

In electron discharge devices, especially in amplifiers such as traveling-wave tubes, backward-wave tubes or klystrons, limitations on application and usefulness are frequently imposed by the inherent noise generation in the electron beam. The tubes may amplify the inherent noise present in the beam to a level which is detrimental to the other functions of the tube. This is true, for example, in traveling-wave devices, and particularly true in traveling-wave amplifiers. A voltage tunable backward-wave amplifier is frequently considered desirable for use in radar receivers, for example. In such a utilization, the maximum range of the radar system is determined by the noise figure of the tube. Thus, it is obviously advantageous to employ tubes having the lowest possible noise figure. Many other advantages of a low noise electron beam device will readily suggest themselves to one skilled in the art. The measure of this noisiness will throughout this specification be designated, as is conventional, by "noise figure" and is defined as the signal-to-noise ratio at the input of the device divided by the signal-to-noise ratio at the output.

Low noise electron guns have heretofore usually consisted essentially of a diode region, that is, an emitting cathode and accelerating anode, followed either by a series of accelerating anodes or a series of drift tubes operated at different potentials. In either case, the purpose of the region beyond the first anode is to minimize and deamplify the noise in the beam. In the former type, this is accomplished as gradually as possible by a change in potential as a function of distance from the cathode. In the latter type, it is accomplished by sudden velocity jumps which tend to minimize velocity fluctuations among the electrons in the stream. In both cases, the initial diode region is designed with considerable effort toward launching the beam in a uniform flow from the forward end of the emitting cathode. The resulting beam has a more or less uniform current density across its width. It has previously been considered to be essential, in accordance with the theoretical models utilized, to launch the electrons as smoothly and evenly forward as possible from the emitting surface. The use of a distorted potential profile, a nonuniform current density or side emission has been regarded as highly harmful to the noise figure of tubes, particularly those employing relatively long electron beams. It has also been considered essential, according to the theoretical models used, that a space charge limited type of emission be utilized in order to smooth out current fluctuations in the beam near the cathode. In fact, all accepted prior art theoretical models have assumed a one-dimensional Fry-Langmuir potential distribution away from the cathode in order theoretically to minimize reduction in shot current and reduction in velocity fluctuations. These models have led to the prediction of a generally accepted minimum

2

theoretical noise figure in the range of 5 to 6 decibels which has been approached in practice and has been considered generally to be the best that could ever be attained (see Proceedings of the I.R.E., vol. 43, pages 981-991, August 1955, "Minimum Noise Figure of Microwave Amplifiers," by H. A. Haus and F. N. H. Robinson).

It is stressed that in all prior art low noise guns electrons are emitted in the direction of the beam. Subsequent to the initial diode region the noise in the beam has in various ways been decreased, as discussed above. Two noise sources in such a beam are shot current and velocity fluctuations. The velocity fluctuations occur because the electrons are emitted with a Maxwell-Boltzmann velocity distribution having shot current noise associated with each of the many different velocity increments. This gives rise to fluctuations in the mean velocity of the beam. For the cathode-anode configuration of the prior art, the velocity distribution of the emitted electrons may be referred to as a "half-Maxwellian" distribution. In other words, electrons are emitted having velocities in the forward direction ranging from zero to positive infinity with the peak of the distribution lying displaced from zero and somewhere in between. The theoretical minimum noise produced in electron streams of the general type provided in traveling-wave tubes, backward-wave tubes and klystrons, is proportional to the average forward velocity component of the electrons at the beam entrance and is proportional to the deviation between the root-mean-square quantity of the forward velocity component and the average forward velocity component. In fact, the theoretical minimum noise figure is proportional to the product of these two quantities. It may be seen that in prior art electron guns the source of noise associated with velocity fluctuations in the beam is thus essentially fixed by the half-Maxwellian velocity distribution which results from the beam being emitted in the forward direction.

A prime object of the present invention is to provide an exceedingly low noise electron gun.

Another object is to provide a low noise electron gun for use in a beam type amplifier device having a noise figure considerably below what has been considered to be the theoretical minimum.

It is another object to provide a low noise electron gun in which the improvement in noise reduction is achieved in the cathode-anode region of the electron beam device.

It is another object to provide a low noise electron gun which provides in the forward direction a velocity distribution of electrons other than the conventional half-Maxwellian distribution.

It is still another object to provide a low noise electron gun in which the average forward velocity component of the electrons in the stream at the initial cathode plane is considerably below what may be obtained in a conventional electron gun.

It is another object to provide a low noise electron gun in which the deviation between root-mean-square quantity of the forward velocity and average forward velocity is substantially decreased below what is possible to achieve in a conventional electron gun.

It is a further object to provide a low noise electron gun arrangement for a traveling-wave type amplifier such that a noise figure is achieved which is superior to that heretofore attainable.

Briefly, these and other objects and advantages of the present invention are achieved in a particular embodiment by providing an arrangement including a side emissive cathode immersed in a relatively strong magnetic field which is coincident with the desired path of the electron beam. The cathode has a front end and a side emissive region lying contiguously rearwardly therefrom. Dis-

posed further along the path and spaced from the cathode is an accelerating electrode having a potential only slightly greater than that of the cathode. Disposed contiguously transversely to and abeam of the emissive region of the cathode and extending both behind and in front thereof is a potential profile-shaping electrode having an inclined surface toward the emitting region or segment of the cathode and diverging away from the path at a predetermined angle. This profile-shaping electrode is maintained at a direct current potential which is more positive with respect to the cathode than is the accelerating electrode. This arrangement of electrodes and relative potentials produces a potential field having a gradient near the edge of the emitting region and having a pronounced radial component tending to pull electrons toward the profile-shaping electrode. However, the strong axial magnetic field and the small forward electric gradient pulls a major portion of the emitting electrons toward the accelerating electrode by the influence of the crossed field effects.

It is to be noted that the electrons emitted from the emissive side of the cathode have a full Maxwellian distribution in the direction of the magnetic field ranging from minus infinity to plus infinity with the peak at zero velocity. Thus, it may be seen that considering only this distribution the average forward velocity component is substantially zero and is thus indeed decreased from that which exists in the conventional half-Maxwellian distribution. It remains, however, to also decrease the deviation between the root-mean-square quantity of the forward velocity and the average forward velocity. This is accomplished by providing a forward component of the electric field by the accelerating electrode which causes a predetermined fraction of the emitted electrons having a negative forward velocity component to be reflected forward in a manner such that their rearward component becomes a forward component of equal magnitude. Those emitted electrons having a forward velocity component algebraically less than this predetermined magnitude are deflected and precluded from entering the beam by the action of the longitudinal magnetic field. After this reflection is accomplished, the maximum of the velocity distribution is still substantially at zero with the average being displaced somewhat therefrom in the positive direction. However, the average velocity is still considerably below the average for a conventional half-Maxwellian distribution and the deviation between root-mean-square quantity of the forward velocity components and the average velocity is also considerably decreased.

The novel features of this invention, as well as the invention itself, both as to its organization and method of operation, will be better understood from the following description taken in conjunction with the accompanying drawings in which like reference numerals refer to like parts and in which:

Referring now to the drawings with more particularity, Fig. 1 illustrates an embodiment of the present invention combining a low noise electron gun with a particular electron beam amplifying device, the particular example chosen being a backward-wave traveling-wave tube amplifier 13, a glass envelope 14 includes an enlarged diameter portion 16 at its left-hand extremity connected to 20 an elongated portion 18 having a lesser diameter. Sealed to the righthand extremity of the elongated portion 18 is a collector electrode 20. Disposed along substantially the length of the elongated portion 18 is a slow-wave structure 22 which is terminated on either end by a 25 matching ferrule 24. Coupled to the input or righthand end of slow-wave structure 22 is a coaxial transmission line 26, the inner connector 28 thereof having a helical extension 30 which is coiled about envelope 14 in a manner to provide a contrawound helical transducer for 30 launching traveling waves onto slow-wave structure 22. Similarly, an output coaxial transmission line 32 is coupled to the output end of slow-wave structure 22 in a manner to couple slow-wave signals off from slow-wave structure 22 and transmit them to a utilization device, not shown.

Disposed within the enlarged portion of the envelope 14 is an electron gun 34 which comprises in this particular example a cylindrical cathode 36 having a substantially planar front end surface 38 at its righthand end and an 40 axially short emissive ring segment 39 on the exterior cylindrical surface of the cathode 36 immediately to the rear of the front end surface 38. Cathode 36 is heated in the conventional manner by a heating electrode 40. A potential profile-shaping electrode 42 is disposed about 45 the cathode 36 in a manner to substantially surround the emissive ring segment 39 and to extend both fore and aft of the emissive segment. The potential profile-shaping electrode 42, along with other elements of the gun 34, may be supported by a set of dielectric rods 44 which maintain axial alignment and mechanical rigidity.

Disposed further along the axis of tube 12 to the right of the potential profile-shaping electrode 42 may be placed a series of accelerating electrodes maintained usually at progressively more positive potentials. Throughout this 55 description, although only three or less such electrodes are shown for purposes of simplification, it is to be understood that a greater number may be used in a particular practical application. The first accelerating electrode 46 is an annular member having an opening 48 of sufficient diameter to permit passage of an electron stream emitted by the cathode 36. Spaced further along the tube 12 are a second and a third accelerating electrode 50 and 51 which have a geometry similar to that of the electrode 46. The three accelerating electrodes are also supported by the dielectric rods 44. The cathode 36 is maintained at a negative potential by a source of potential 52, the negative terminal of which may be connected to the cathode 36. At an appropriate tap, the heating electrode 40 is also connected to the source 52. The first accelerating electrode 46 is maintained at a positive potential with respect to the cathode by a connection to an appropriate tap, as shown, to the source 52. The profile-shaping electrode 42 is connected to the source 52 at a next more positive tap. The second and third accelerating electrodes

50 and 51 are maintained, respectively, next more positive by appropriate taps also to the source 52. The slow-wave structure 22 may be maintained next more positive, as shown, by connecting it to ground potential through an isolating resistor 54.

Surrounding substantially the entire length of the traveling-wave tube 12 is a focusing magnet 56 which may be a solenoid as shown and which is energized by the source of potential 58. The magnet 56 extends over the electron gun 34 and immerses it in a strong axial constraining magnetic field so that electrons which would tend to be drawn radially outward toward the profile-shaping electrode 42 are instead constrained to flow in the axial direction along the length of the traveling-wave tube 12 and within the slow-wave structure 22. The electrons are eventually intercepted by the collector electrode 20 which dissipates their kinetic energy and conducts them to ground through a source of potential 60. The source 60 is connected with its positive terminal to the collector 20 so that secondarily emitted electrons will not drift backwardly into the interaction region of the slow-wave structure 22 and cause added shot noise or other deleterious effects.

Fig. 2 illustrates generally the geometrical relationships which are considered to be fundamental in an explanation of the structure of the electron gun of the present invention. A cathode 62 has an emitting surface 64 lying within an axially short segment 66 on the side of the cathode 62. The emissive surface 64 lies adjacent to the front end surface 65 of the cathode 62 and rearwardly therefrom with respect to the axial path of the electron stream 68. The cathode 62 is maintained at a reference potential of zero volts. A profile-shaping electrode surface 70 is disposed transversely from the path and extends axially both behind and in front of the emissive segment 66. The surface 70 is inclined in a manner to be exposed toward the emissive segment 66 and diverges along the direction of the electron stream 68 forming an acute angle therewith. The profile-shaping electrode surface 70 is maintained at a direct current potential V_2 of a few volts positive with respect to the cathode 62 which is designated as being of potential V_0 . Disposed further along the path of the electron stream 68 from the profile-shaping electrode surface 70 is an accelerating electrode 72 which is placed adjacent to the electron stream and maintained at a direct current potential V_1 which is a few volts positive and algebraically intermediate V_0 and V_2 . The entire structure of Fig. 2 is immersed in a strong axial magnetic field H which is parallel to the electron stream 68.

Referring now to Fig. 3, there is shown a sheet-beam forming electron gun in which a cathode 74 has a side emissive surface 76 which is included within a short axial emissive segment 78 of the cathode 74, segment 78 lying adjacently rearward of the front end thereof. A potential profile-shaping electrode 80 is disposed symmetrically above and below the emissive segment 78 and has inclined potential profile-shaping surfaces 82 which are exposed toward the emissive segment 78 and diverge along the path of the electron stream 84. The surfaces 82 are contiguous to the cathode 74 and extend both fore and aft of the emissive segment 78. Disposed axially to the right, in Fig. 3, of profile-shaping electrode 80 is an accelerating electrode 86 which is oriented perpendicularly to the path of the electron stream 84 and is contiguous thereto. A cathode 74 is maintained at a direct current potential of zero designated in the figure as V_0 . The accelerating electrode 86 is maintained at a direct current potential V_1 which is slightly positive with respect to the cathode 74; and the profile-shaping electrode 80 is maintained at a direct current reference potential V_2 which is next more positive with respect to the cathode. Again, the entire configuration of Fig. 3 is immersed in a strong axial magnetic field designated H .

Referring to Fig. 4, there is shown a generalized cylind-

rical embodiment of the low noise electron gun of the present invention. A cylindrical cathode 88 is axially aligned with the path of electron stream 90 and is maintained at a direct current reference potential V_0 equal to zero. The cathode 88 has a side emissive surface 92 adjacent its righthand extremity which is oriented substantially in a plane perpendicular to the path of the stream 90. Disposed concentrically about the emissive surface 92 is a potential profile-shaping electrode surface 94 having the form of a frusto-conical surface of revolution about the axis of the stream 90. The determining planes of the conical frustum lie respectively fore and aft of and parallel to the side emitting surface 92. Disposed to the right in the figure along the path of the electron stream 90 is an accelerating electrode 96 having an inner circular aperture which is contiguously concentric about the electron stream 90 and which is perpendicularly oriented with respect thereto. The accelerating electrode 96 is maintained at a direct current potential V_1 which is slightly positive with respect to the cathode, and the potential profile-shaping electrode 94 is maintained more positive at a potential designated V_2 . Again, the entire configuration is immersed in a strong axial constraining magnetic field H .

Referring now to Fig. 5, there is shown a different embodiment of a cylindrical beam gun which includes a cylindrical cathode 98 having a side emissive ring surface 100 lying within an axially short side emissive segment 102. A potential profile-shaping electrode 104 is disposed perpendicularly to the axis of the cathode 98 and has a coaxial frusto-conical aperture 106 disposed about the cathode 98 and extending both forwardly and rearwardly of the side emissive segment 102. The frusto-conical surface of aperture 106 is contiguous to the side emissive segment 102 and diverges in the direction of the electron stream 107. The aperture 106 may comprise also surfaces 108 and 110 which are, in this particular example, cylindrical surfaces concentric with the axis of the cathode 98 and which join to the smaller and larger ends of the frusto-conical surface, respectively. Disposed to the right of the profile-shaping electrode 104 is an accelerating electrode 112 which has a circular aperture 114 concentric with and disposed contiguously about the electron stream 107 emitted by the cathode 98. The cathode 98 is maintained at a direct current potential V_0 equal to zero; the profile-shaping electrode 104 is maintained at a direct current potential V_2 which is positive with respect to the cathode; and the accelerating electrode 112 is maintained at a direct current potential V_1 which is algebraically intermediate to potentials V_0 and V_2 . The cathode 98 with its side emissive ring surface 100, the profile-shaping electrode 104, and the accelerating electrode 112 are immersed in a strong axial constraining magnetic field H .

Although it is obvious that the electron stream 107 emitted by the embodiment depicted in Fig. 5 is hollow due to the side emission, Fig. 6 represents an embodiment of a cylindrical beam forming electron gun which produces two concentric hollow electron streams 116 and 117. An annular cathode 118 is maintained at a direct current reference potential V_0 equal to zero volts and is immersed in a strong axial constraining magnetic field H . A potential profile-shaping electrode 120 having a substantially coplanar inner portion 122 is disposed perpendicularly to the axis of the cathode 118 and is axially oriented so as to extend both fore and aft of the side emissive segments 119 near the righthand end of the cathode 118. The profile-shaping electrode 120 has a circular aperture which comprises a frusto-conical surface of revolution 126 disposed concentrically about and radially contiguous to the cathode 118. The profile-shaping electrode portion 122 comprises an outer frusto-conical surface of revolution which is concentric with the cathode 118 and, as previously mentioned, is substantially coplanar with the remainder of profile-shaping electrode

120. The frusto-conical surface of profile-shaping electrode 120 diverges at a predetermined angle in the direction of the electron streams 116 and 117; and the frusto-conical surface of the inner electrode 122 converges at the same predetermined angle along the direction of the electron stream. Disposed perpendicularly to the electron stream 116 and spaced therealong to the right of the profile-shaping electrode 120 is a first accelerating electrode 128 which has an annular aperture 130 concentric with and adjacent radially to the electron stream 117. Disposed further yet along the path of the electron stream is a second accelerating electrode 132 which is similarly oriented and has similar geometry with respect to the accelerating electrode 128. One or more additional accelerating electrodes may also be utilized here.

Referring now to Fig. 7, there is shown in more detail the dimensions and relationships of a low noise electron gun constructed in accordance with the invention. The cathode 134 is disposed along the axis of the electron stream 136 and has a side emissive ring portion 138 which is substantially planar and lies substantially perpendicularly to the axis of the electron stream 136. The emissive ring 138 lies substantially immediately to the rear of the righthand end, as seen in the figure, of the cathode 134. The cathode 134 has a diameter, or transverse dimension, D and is maintained at a direct current potential V_0 equal to zero. A potential profile-shaping electrode 140 is disposed about and lies between a transverse plane 142 which is aft of the emitting ring portion 138 by a distance a and a transverse plane 144 which is forward of the emitting ring portion 138 by a distance designated b . The surface of the profile-shaping electrode exposed toward the emissive ring portion 138 is inclined at an angle β from the axis of the cathode 134. The edge of the profile-shaping electrode 140, designated by the plane 142, is spaced from the cathode 134 by a distance designated e . Spaced forwardly from the plane 144 by a distance c is an accelerating electrode 146 which is disposed symmetrically above and below, or around, the electron stream 136 and is maintained at a direct current potential V_1 . A potential profile-shaping electrode 140 is maintained at a direct current reference potential of V_2 . Some typical ranges for the dimensions and voltages for optimum noise reduction in a practical embodiment constructed substantially in accordance with the geometry of Fig. 7 are:

- a —Between .005 inch and .200 inch;
- b —Between .005 inch and .060 inch;
- c —Between .20 inch and .100 inch;
- d —Between .005 inch and .200 inch;
- e —Between .003 inch and .070 inch;
- β —Between 30° and 75° ;
- V_0 —Zero volts;
- V_2 —Between plus 3 and plus 20 volts;
- V_1 —At or below V_2 .

These dimensions and voltage ranges are not given as designating the limits for their respective parameters, but are merely given as empirical numbers which have proven to be especially successful in achieving noise reduction in electron guns constructed in accordance with the present invention.

Referring now to Fig. 8, there is shown a pictorial graph of relative electron current density on the horizontal scale versus position across the electron stream 150 of a typical side emitting cathode 152 as shown by the curve 148. The curve is seen to be at a maximum off the edge of the cathode and decreases to a minimum in either direction from the positioning maximum.

Fig. 9 shows a pictorial plot similar to that of Fig. 8 in which a curve 154 plots relative electron current density horizontally versus radial position across the electron stream 156 of an annular beam forming cathode 158. The profile-shaping electrodes are not shown in either of Figs. 8 or 9, but the electron current density

plots shown exist by virtue of a potential profile-shaping electrode surface such as shown in the other figures which is symmetrically disposed about the side emitting portions of the cathode schematically shown in Figs. 8 and 9, and by virtue of the unique potential distribution among the various electron gun electrodes. Again, in Fig. 9 it is seen that the electron current density is greatest just off the edges of the cathode 158 and decreases to a minimum in either radial direction therefrom.

Referring to Fig. 10, there is shown an embodiment of the present invention utilizing a negative grid probe 160 coaxially disposed within a hollow side emissive cathode 162. Emissive material 164 is disposed on the outer cylindrical surface of cathode 162 near the front end or righthand end, as seen in the figure. A profile-shaping electrode 166 is disposed about the emissive material 164 similarly to the manner depicted in the previous figures. The grid probe 160 is maintained at a direct current potential which is negative with respect to that of the cathode 162, as indicated by the connection of a battery 168 connected with its negative terminal to the probe 160 and its positive terminal to the cathode 162. The negative potential on the probe 160 aids in preventing the migration of the emissive material 164 from its position on the cylindrical surface of the cathode 162 to the front end, planar surface to thus preclude all but a substantially pure side emission from the cathode 162.

In the operation of a low noise electron beam device of the present invention, of which the backward-wave amplifier of Fig. 1 is described as an example, microwave energy is delivered to the traveling-wave tube 12 along the coaxial transmission line 26. From the helical transducer 30 a traveling wave is launched upon slow-wave structure 22 and is caused to interact therealong in a well-known manner with an electron beam projected from the electron gun 34 along the helix 22. The microwave energy in the form of the traveling-wave having experienced interaction with the electron stream normally in a manner to achieve amplification is then coupled off of the helix 22 by the helical transducer at the lefthand end, in Fig. 1, of the traveling-wave tube 13 and transmitted via the transmission line 32 to a utilization device, not shown.

Referring to the operation of the low noise side emission electron gun 34, the cathode 36 is heated by current flowing through its heater coil causing thermal emission of electrons from the side emissive area 39. The surrounding profile-shaping electrode 42 being maintained at a positive potential tends to cause electrons to be pulled radially outward toward it. However, the strong magnetic constraining field maintained by the solenoid 56 and the electric field from the slightly positive accelerating electrode 46 cause a predetermined proportion of the emitted electrons to spiral and travel forwardly along the beam path toward the collector end of the tube 13. It is to be noted that the inclined surface of the profile-shaping electrode is maintained at a higher potential than the first accelerating electrode 46 in order to enhance the side emission from the emissive surface 39.

In order to describe in more detail the operation of the side emitting cathode of the present invention, reference is now made to Figs. 11 and 12 of the drawing. Fig. 11 is a plot of the conventional Maxwell-Boltzmann distribution of electrons emitted in the direction of the electron stream of a prior art electron gun. The relative amount of current in an infinitesimal increment of velocity is plotted on the ordinate, versus magnitude of electron velocity on the abscissa. It is seen that the average velocity lies well to the right of the origin and is designated as $\bar{v}$ on the figure. It is also indicated on this figure that the deviation between the root-mean-square quantity of the velocity and the average velocity $\bar{v}$ is of a relatively large magnitude.

Referring to Fig. 12, on the other hand, there is

plotted a full, nonconventional Maxwell-Boltzmann distribution of electron velocity in the direction of the beam which is characteristic of the present invention. Plotted on the ordinate again is a relative amount of current in a given velocity increment versus magnitude of velocity in the direction of the electron stream on the abscissa. It may be seen that since this direction is parallel to the emitting surface of the electrons they may have such a distribution of velocities ranging from negative infinity to positive infinity with a peak at the origin which also represents the average velocity $\bar{v}$. It may also be understood that a plot of electron velocity distribution in the transverse direction would be one similar to that depicted by Fig. 11. However, in the present invention all of the energy thus represented is transmuted into rotational energy as the transverse component of velocity is caused to spiral about the direction of the strong magnetic field and hence will not further be considered in the present description.

As discussed above in the introduction, the theoretical minimum noise figure is proportional to the average electron velocity, the deviation between root-mean-square of the forward velocities of electrons traveling in the direction of the beam and the average velocity in that direction and to the product of these two quantities. It is indicated on Fig. 12 that the deviation quantity represented by the spacing between $\bar{v}$ and

$$\sqrt{v^2}$$

is considerably decreased from the similar deviation shown in Fig. 11.

In accordance with the present invention, it may be seen that of the electrons represented by the distribution of Fig. 12, all those having a positive velocity in the direction of this stream will find their way into the stream. It may further be seen that electrons having a velocity algebraically less than a critical velocity v' determined by the magnitude of the forward directed electric field of the first accelerating electrode will be lost from the beam because these electrons will spiral into the cathode and be lost. However, electrons having a velocity in the forward direction algebraically greater than v' will be pulled forwardly by the electric field of the first accelerating electrode and form a part of the beam. All the electrons having velocities between v' and zero will obviously, when thus reflected forwardly, have identical velocities in the opposite direction as by a conservative field reflection. The resultant beam then has the velocity distribution indicated by the dotted line 168 of Fig. 12. It may now be seen that the average velocity $\bar{v}$ in the forward direction is considerably lower than that of the conventional velocity distribution depicted in Fig. 11.

Thus it is possible to substantially decrease the theoretical minimum noise figure of an electron beam device in accordance with the present invention by altering the basic velocity distribution of the emitted electrons at the cathode. In prior art electron guns the source of noise relating to velocity fluctuations and shot current in the beam was essentially fixed by the conventional half-Maxwellian velocity distribution. It is stressed that this half-Maxwellian velocity distribution results from the beam being emitted in the direction of the stream while in the present invention it is avoided by emitting the electrons predominantly transversely to the direction of the electron stream. By utilizing such side emission, it is possible to grasp a greater fraction of the total number of electrons at low velocities.

An analysis of the electron velocities in an electron gun of the present invention has shown that the product of the average velocity in the forward direction at the cathode and the deviation between the root-mean-square quantity of the forward velocity and the average forward velocity at the cathode may, by adjusting the magnetic and electric fields in a manner to choose an optimum

value of the velocity parameter v' , be reduced to about 42 percent of the value of that in a conventional low noise gun. This typically reduces the theoretical minimum noise figure from about 6 decibels to approximately 5.3 decibels.

There has thus been disclosed a new and useful low noise electron gun in an electron beam device of such improved character as to achieve a noise figure vastly lower than what has heretofore been considered theoretically possible. Conventional theoretical models have been departed from to provide a basically different structure with, among others, the attendant advantages discussed above.

What is claimed as new is:

15. A low noise electron gun for providing an electron beam in a forward direction along a predetermined lineal path comprising: a side emissive cathode for emitting electrons in substantially all outward velocities from said side emissive cathode; means for providing a constraining magnetic field about said cathode in said forward direction along said path; a profile-shaping electrode disposed contiguously to said cathode at right angles therefrom with respect to said path, said profile-shaping electrode having a surface inclined toward said cathode and toward said forward direction, said surface forming an acute angle therewith; an accelerating electrode disposed adjacent to said path and spaced from said profile-shaping electrode, said cathode being at a reference potential of zero volts, said accelerating electrode being at a potential positive with respect to said cathode, said profile-shaping electrode being at a potential positive with respect to said accelerating electrode whereby electrons are emitted from the side of said cathode lying toward said profile-shaping electrode, those emitted with a rearward velocity component of greater than a predetermined magnitude being precluded from entering said beam while electrons having a rearward velocity component less than said predetermined magnitude are reflected into and constrained to flow along said beam.
20. A low noise electron gun for projecting a stream of electrons in a forward direction along a predetermined path comprising: a side emissive cathode having an emissive surface lying within a longitudinally short segment along said path for emitting electrons having substantially all outward velocities from the side of said emissive cathode; a profile-shaping electrode disposed from said emissive segment transversely to said path and having a longitudinal length which is greater than the length of said emissive segment and which extends both fore and aft of said emissive segment, said profile-shaping electrode having an inclined surface exposed toward said axial segment which forms an acute angle with said forward direction; means for providing a constraining magnetic field about said cathode parallel to said predetermined path, and an accelerating electrode disposed also transversely from said path and forward of said profile-shaping electrode, said cathode being maintained at a direct current reference potential of zero volts, said accelerating electrode being maintained at a direct current potential which is positive with respect to said cathode and said profile-shaping electrode being maintained at a direct current potential which is positive with respect to that of said accelerating electrode whereby the electrons emitted from said emissive segment of said side emissive cathode having a rearward velocity component of more than a predetermined magnitude are precluded from entering said stream, while electrons having a rearward velocity component less than said predetermined magnitude are reflected into said stream.
25. A backward-wave amplifier comprising: an elongated envelope disposed about a longitudinal axis; a slow-wave structure within said envelope, said slow-wave structure having an emitter end and a collector end; collector means disposed at the collector end of said
30. A low noise electron gun for providing an electron beam in a forward direction along a predetermined lineal path comprising: a side emissive cathode for emitting electrons in substantially all outward velocities from said side emissive cathode; means for providing a constraining magnetic field about said cathode in said forward direction along said path; a profile-shaping electrode disposed contiguously to said cathode at right angles therefrom with respect to said path, said profile-shaping electrode having a surface inclined toward said cathode and toward said forward direction, said surface forming an acute angle therewith; an accelerating electrode disposed adjacent to said path and spaced from said profile-shaping electrode, said cathode being at a reference potential of zero volts, said accelerating electrode being at a potential positive with respect to said cathode, said profile-shaping electrode being at a potential positive with respect to said accelerating electrode whereby electrons are emitted from the side of said cathode lying toward said profile-shaping electrode, those emitted with a rearward velocity component of greater than a predetermined magnitude being precluded from entering said beam while electrons having a rearward velocity component less than said predetermined magnitude are reflected into and constrained to flow along said beam.
35. A low noise electron gun for projecting a stream of electrons in a forward direction along a predetermined path comprising: a side emissive cathode having an emissive surface lying within a longitudinally short segment along said path for emitting electrons having substantially all outward velocities from the side of said emissive cathode; a profile-shaping electrode disposed from said emissive segment transversely to said path and having a longitudinal length which is greater than the length of said emissive segment and which extends both fore and aft of said emissive segment, said profile-shaping electrode having an inclined surface exposed toward said axial segment which forms an acute angle with said forward direction; means for providing a constraining magnetic field about said cathode parallel to said predetermined path, and an accelerating electrode disposed also transversely from said path and forward of said profile-shaping electrode, said cathode being maintained at a direct current reference potential of zero volts, said accelerating electrode being maintained at a direct current potential which is positive with respect to said cathode and said profile-shaping electrode being maintained at a direct current potential which is positive with respect to that of said accelerating electrode whereby the electrons emitted from said emissive segment of said side emissive cathode having a rearward velocity component of more than a predetermined magnitude are precluded from entering said stream, while electrons having a rearward velocity component less than said predetermined magnitude are reflected into said stream.
40. A low noise electron gun for providing an electron beam in a forward direction along a predetermined lineal path comprising: a side emissive cathode for emitting electrons in substantially all outward velocities from said side emissive cathode; means for providing a constraining magnetic field about said cathode in said forward direction along said path; a profile-shaping electrode disposed contiguously to said cathode at right angles therefrom with respect to said path, said profile-shaping electrode having a surface inclined toward said cathode and toward said forward direction, said surface forming an acute angle therewith; an accelerating electrode disposed adjacent to said path and spaced from said profile-shaping electrode, said cathode being at a reference potential of zero volts, said accelerating electrode being at a potential positive with respect to said cathode, said profile-shaping electrode being at a potential positive with respect to said accelerating electrode whereby electrons are emitted from the side of said cathode lying toward said profile-shaping electrode, those emitted with a rearward velocity component of greater than a predetermined magnitude being precluded from entering said beam while electrons having a rearward velocity component less than said predetermined magnitude are reflected into and constrained to flow along said beam.
45. A low noise electron gun for projecting a stream of electrons in a forward direction along a predetermined path comprising: a side emissive cathode having an emissive surface lying within a longitudinally short segment along said path for emitting electrons having substantially all outward velocities from the side of said emissive cathode; a profile-shaping electrode disposed from said emissive segment transversely to said path and having a longitudinal length which is greater than the length of said emissive segment and which extends both fore and aft of said emissive segment, said profile-shaping electrode having an inclined surface exposed toward said axial segment which forms an acute angle with said forward direction; means for providing a constraining magnetic field about said cathode parallel to said predetermined path, and an accelerating electrode disposed also transversely from said path and forward of said profile-shaping electrode, said cathode being maintained at a direct current reference potential of zero volts, said accelerating electrode being maintained at a direct current potential which is positive with respect to said cathode and said profile-shaping electrode being maintained at a direct current potential which is positive with respect to that of said accelerating electrode whereby the electrons emitted from said emissive segment of said side emissive cathode having a rearward velocity component of more than a predetermined magnitude are precluded from entering said stream, while electrons having a rearward velocity component less than said predetermined magnitude are reflected into said stream.
50. A low noise electron gun for providing an electron beam in a forward direction along a predetermined lineal path comprising: a side emissive cathode for emitting electrons in substantially all outward velocities from said side emissive cathode; means for providing a constraining magnetic field about said cathode in said forward direction along said path; a profile-shaping electrode disposed contiguously to said cathode at right angles therefrom with respect to said path, said profile-shaping electrode having a surface inclined toward said cathode and toward said forward direction, said surface forming an acute angle therewith; an accelerating electrode disposed adjacent to said path and spaced from said profile-shaping electrode, said cathode being at a reference potential of zero volts, said accelerating electrode being at a potential positive with respect to said cathode, said profile-shaping electrode being at a potential positive with respect to said accelerating electrode whereby electrons are emitted from the side of said cathode lying toward said profile-shaping electrode, those emitted with a rearward velocity component of greater than a predetermined magnitude being precluded from entering said beam while electrons having a rearward velocity component less than said predetermined magnitude are reflected into and constrained to flow along said beam.
55. A low noise electron gun for projecting a stream of electrons in a forward direction along a predetermined path comprising: a side emissive cathode having an emissive surface lying within a longitudinally short segment along said path for emitting electrons having substantially all outward velocities from the side of said emissive cathode; a profile-shaping electrode disposed from said emissive segment transversely to said path and having a longitudinal length which is greater than the length of said emissive segment and which extends both fore and aft of said emissive segment, said profile-shaping electrode having an inclined surface exposed toward said axial segment which forms an acute angle with said forward direction; means for providing a constraining magnetic field about said cathode parallel to said predetermined path, and an accelerating electrode disposed also transversely from said path and forward of said profile-shaping electrode, said cathode being maintained at a direct current reference potential of zero volts, said accelerating electrode being maintained at a direct current potential which is positive with respect to said cathode and said profile-shaping electrode being maintained at a direct current potential which is positive with respect to that of said accelerating electrode whereby the electrons emitted from said emissive segment of said side emissive cathode having a rearward velocity component of more than a predetermined magnitude are precluded from entering said stream, while electrons having a rearward velocity component less than said predetermined magnitude are reflected into said stream.
60. A low noise electron gun for providing an electron beam in a forward direction along a predetermined lineal path comprising: a side emissive cathode for emitting electrons in substantially all outward velocities from said side emissive cathode; means for providing a constraining magnetic field about said cathode in said forward direction along said path; a profile-shaping electrode disposed contiguously to said cathode at right angles therefrom with respect to said path, said profile-shaping electrode having a surface inclined toward said cathode and toward said forward direction, said surface forming an acute angle therewith; an accelerating electrode disposed adjacent to said path and spaced from said profile-shaping electrode, said cathode being at a reference potential of zero volts, said accelerating electrode being at a potential positive with respect to said cathode, said profile-shaping electrode being at a potential positive with respect to said accelerating electrode whereby electrons are emitted from the side of said cathode lying toward said profile-shaping electrode, those emitted with a rearward velocity component of greater than a predetermined magnitude being precluded from entering said beam while electrons having a rearward velocity component less than said predetermined magnitude are reflected into and constrained to flow along said beam.
65. A low noise electron gun for projecting a stream of electrons in a forward direction along a predetermined path comprising: a side emissive cathode having an emissive surface lying within a longitudinally short segment along said path for emitting electrons having substantially all outward velocities from the side of said emissive cathode; a profile-shaping electrode disposed from said emissive segment transversely to said path and having a longitudinal length which is greater than the length of said emissive segment and which extends both fore and aft of said emissive segment, said profile-shaping electrode having an inclined surface exposed toward said axial segment which forms an acute angle with said forward direction; means for providing a constraining magnetic field about said cathode parallel to said predetermined path, and an accelerating electrode disposed also transversely from said path and forward of said profile-shaping electrode, said cathode being maintained at a direct current reference potential of zero volts, said accelerating electrode being maintained at a direct current potential which is positive with respect to said cathode and said profile-shaping electrode being maintained at a direct current potential which is positive with respect to that of said accelerating electrode whereby the electrons emitted from said emissive segment of said side emissive cathode having a rearward velocity component of more than a predetermined magnitude are precluded from entering said stream, while electrons having a rearward velocity component less than said predetermined magnitude are reflected into said stream.
70. A backward-wave amplifier comprising: an elongated envelope disposed about a longitudinal axis; a slow-wave structure within said envelope, said slow-wave structure having an emitter end and a collector end; collector means disposed at the collector end of said

slow-wave structure; an electron gun housing coupled to the emitter end of said envelope and defining an enclosure for an electron gun assembly; input and output radio frequency coupling means contiguously disposed about said envelope at different points therealong; magnet means for providing a strong axial constraining magnetic field throughout the length of said electron gun assembly; and an electron gun assembly mounted within said electron gun enclosure, said assembly including a cylindrical cathode mounted along the longitudinal axis of said amplifier, the axis of said cathode coinciding with the axis of said amplifier and the end of said cathode which is closest the collector end of said slow-wave structure lying in a plane transverse to said axes; an emissive surface disposed in a ring on the outer surface of said cathode, the ring of emissive material lying substantially in a plane transverse to the axis of said cathode and spaced at a predetermined distance from said collector end of said cathode, the potential of said cathode being at a reference of zero volts, electrons traveling from said emissive surface along the axis of said amplifier thereby providing a cylindrical, hollow stream of electrons passing along the length of said slow-wave structure to the collector end thereof; a first, profile-shaping, annular electrode disposed about and concentric with the ring of emissive material on said cathode, the inner surface of said first electrode extending from a point which is further from the collector end on one side of said ring of emissive material to a point which is nearer the collector end on the other side of said ring, said inner surface defining a frusto-conical surface of revolution which diverges in the direction toward the collector end and whose axis is coincident with the longitudinal axis of said amplifier, said profile-shaping electrode being maintained at a potential of approximately five volts with respect to said cathode; a first, planar anode spaced along the path of the stream of electrons at a pre-selected distance from said ring of emissive material and substantially parallel to the plane thereof, said first anode including an internal aperture, the surfaces defining said aperture being adjacent to and concentric with the hollow stream of electrons, said first anode being maintained at a potential of substantially four volts with respect to said cathode, and a plurality of further accelerating anodes mounted in successive planes transverse to the longitudinal axis of said amplifier and disposed successively further along the stream of electrons away from said cathode, each of said plurality of anodes having an internal surface defining an aperture extending about, adjacent to, and concentric with said hollow stream of electrons and each being maintained at a different potential, said potentials increasing incrementally in correspondence to the position of the anode along said stream of electrons.

4. A low noise electron gun for producing a stream of electrons along a predetermined path comprising: means for providing a constraining magnetic field along said path; a side emissive cathode disposed at one end of said path; an accelerating electrode disposed along said path and spaced from said cathode; a profile shaping electrode disposed contiguous to and a beam from said cathode and having a surface inclined towards said cathode and said path at an angle with said path of 70 to 35 degrees and extending forwardly from said cathode .005 to .060 inch, said cathode being maintained at a reference potential of zero volts, said accelerating electrode being maintained at a potential positive with respect to said cathode; said profile shaping electrode being maintained at a potential positive with respect to said accelerating electrode whereby electrons are emitted from the side of said side emissive cathode, those electrons emitted with a forward velocity component algebraically less than a predetermined magnitude being precluded from entering said stream while electrons having a forward velocity component greater than said pre-

determined magnitude are constrained to flow along said predetermined path.

5. A low noise sheet-beam electron gun for projecting a stream of electrons along a predetermined axial path comprising: a rectangular side emissive cathode having a planar front end surface disposed transversely to said path and having an axially short emissive segment disposed rearwardly of said front end surface; a profile shaping electrode disposed substantially parallel to said planar front end surface and contiguously about said cathode and having an axial thickness which is greater than the axial length of said axially short emissive section, said profile shaping electrode having an inclined planar surface exposed toward said axial segment and toward the direction of said path; an accelerating electrode disposed substantially parallel to said profile shaping electrode contiguously to said path and axially spaced from said profile shaping electrode along said path; and means for providing a relatively strong axial magnetic field throughout at least the region defined by the rear of said profile shaping electrode and the front of said accelerating electrode, said cathode being maintained at a direct current reference potential of zero, said accelerating electrode being maintained at a direct current potential positive with respect thereto and said profile shaping electrode being maintained at a direct current potential positive with respect to said accelerating electrode.

6. A low noise electron gun for projecting a stream of electrons along an axial path in a predetermined direction comprising: a cylindrical cathode having an end portion substantially perpendicular to said axial path and an axially short emissive segment on the cylindrical surface of said cathode rearwardly from said end portion of said cathode; a profile shaping electrode disposed concentrically about said emissive segment and extending fore and aft thereof along said path, said profile shaping electrode comprising a frusto-conical internal surface of revolution concentric about said axial path and being exposed 40 toward said emitting segment and diverging toward said direction; an accelerating electrode comprising a transverse sheet having an aperture concentric with said path, disposed transversely thereto, and spaced from said profile shaping electrode along said path; and means for providing an axial constraining magnetic field through at least the region defined by the rear of said profile shaping electrode and the front of said accelerating electrode, said cathode being maintained at a direct current reference potential of zero, said accelerating electrode being maintained at a direct current reference potential positive with respect to that of said cathode and said profile-shaping electrode being maintained at a direct current reference potential positive with respect to that of said accelerating electrode.

55. A low noise electron gun for producing a hollow cylindrical stream of electrons along an axial path in a predetermined direction comprising: a profile shaping electrode having a frusto-conical internal surface of revolution concentric about said axial path and diverging in said 60 direction at a predetermined angle, the conical frustum being limited by first and second planes perpendicular to said axial path, said profile shaping electrode further comprising a second conical surface lying substantially between said first and second planes radially within said frusto-conical surface and converging at said predetermined angle in said predetermined direction, said frusto-conical and said conical surfaces being spaced from each other by a predetermined annular spacing; a cylindrical annular side emitting cathode concentric about said axial path and having an axially short emissive segment comprising an emitting circle on the external surface of said cylindrical cathode and a concentric emitting circle on the inner surface of said cylindrical cathode, said cathode being disposed in the annular spacing between said frusto-conical surface and said conical surface such that

said emissive segment lies between said first and second planes; an accelerating electrode disposed substantially in a plane perpendicular to said axial path and spaced axially therealong from said profile shaping electrode, said accelerating electrode having an annular opening concentric about said axial path, said annular opening being disposed contiguously to both the inner and the outer surfaces of said hollow electron stream; and means for providing an axial constraining magnetic field throughout the region including said cathode and said accelerating electrode, said accelerating electrode being maintained at a direct current reference potential of zero, said cathode being negative with respect thereto and said profile shaping electrode being positive with respect thereto, whereby the electrons are emitted from said emitting segment of said cathode toward said frusto-conical and said conical surfaces and are in part constrained by said magnetic field to flow along said axial path in said predetermined direction.

8. A low noise electron gun for providing a cylindrical beam of electrons along an axial path in a predetermined direction comprising: a cylindrical side emissive cathode member having a ring shaped emitting portion and a substantially planar end, said emitting ring portion lying on the surface of said cylindrical cathode contiguously rearwardly of said planar end; a profile shaping electrode concentric with said cathode disposed between first and second planes transverse to said axial path, said first plane lying aft of said emitting ring portion by .001 to .550 inches and said second plane lying forwardly of said emitting ring portion by .001 to .100 inch and having a frusto-conical internal surface of revolution disposed symmetrically about said axial path at an angle of 40 to 50 degrees therewith and extending between said planes and having a minimum diameter at said first plane and the maximum diameter at said second plane thereby diverging along said axial path, the end of said frusto-conical surface having said minimum diameter being radially spaced from said cathode by a distance of from .001 to .100 inch; an accelerating electrode lying substantially in a plane transverse to said path and spaced therealong from said profile shaping electrode and having a circular aperture contiguously concentric about said axial path; and means for providing an axial constraining magnetic field between said first plane and said accelerating electrode, said cathode being maintained at a direct current reference potential of zero, said accelerating electrode being maintained at a direct current

- potential of the order of 3 volts positive with respect thereto and said profile shaping electrode being maintained at a direct current potential of the order of 5 volts positive with respect to said cathode electrode.
- 5 9. A low noise electron gun for providing a cylindrical beam of electrons along an axial path in a predetermined direction comprising: a hollow cylindrical cathode member having a forward end and an axially short emissive cylindrical surface on the outer surface of said cylindrical cathode contiguously rearward from said end; a cylindrical grid probe electrode lying within said hollow cathode concentric therewith and extending into the region of said end of said hollow cylindrical cathode member; a profile shaping electrode concentric with said cathode 10 disposed between first and second planes transverse to said axial path, said first plane lying aft of said emissive surface of said cylindrical cathode and said second plane lying forward thereof and having a frusto-conical surface of revolution disposed concentrically about said axial 15 path and extending between said planes and diverging in the forward direction along said axial path; an accelerating electrode lying substantially in a plane transverse to said path spaced therealong from said profile shaping electrode and having a circular aperture concentrically 20 contiguous about said axial path; and means for providing an axial constraining magnetic field throughout at least the region between said first plane and said accelerating electrode, said accelerating electrode being maintained at a direct current reference potential of 25 zero, said cathode being maintained negative with respect thereto, said grid probe electrode being maintained negative with respect to said cathode and said profile shaping electrode being maintained positive with respect to said accelerating electrode.
